UNITED STATES PATENT OFFICE.

WILLIAM F. BOKUM AND HERBERT V. COULSTON, OF PHILADELPHIA, PENNSYLVANIA, ASSIGNORS TO SMITH AND FURBUSH MACHINE COMPANY, OF PHILADELPHIA, PENNSYLVANIA, A CORPORATION OF PENNSYLVANIA.

GARNETT MACHINE.

1,401,863.

Specification of Letters Patent. Patented Dec. 27, 1921.

Application filed November 12, 1919. Serial No. 337,388.

To all whom it may concern:

Be it known that we, WILLIAM F. BOKUM and HERBERT V. COULSTON, citizens of the United States, residing at Philadelphia, 5 Pennsylvania, have invented certain Improvements in Garnett Machines, of which the following is a specification.

Our invention relates to certain improvements in Garnett machines.

10 One object of the invention is to provide a series of separate plates, or shoes, which are secured to the arch of a Garnett machine and on which the poppets are adjustably mounted so as to provide means for adjusting the rolls on account of variations in the diameter of said rolls.

15 A further object of the invention is to make the adjustable plates of struck up sheet metal. Heretofore, it has been the 20 general practice in manufacturing Garnett machines to form the projections, or lugs, as abutments for the lateral adjusting screws and as a bearing for the longitudinal adjusting screws integral with the arch. 25 By having the separate plates, the plates can be adjusted and held in the position to which they are adjusted. In the event of breakage, one plate can be detached and another plate substituted for it.

30 In the accompanying drawings:

Figure 1 is a side view of sufficient of a Garnett machine to show a portion of the arch and the plates secured thereto;

Fig. 2 is a sectional view on the line 2—2, 35 Fig. 1;

Fig. 3 is a perspective view of one of the detachable plates;

Fig. 4 is a perspective view showing the rear of the plate illustrated in Fig. 3;

40 Fig. 5 is a view of one of the fixed nuts for the reception of the longitudinal adjusting screw; and

Fig. 6 is a view of a blank from which the plates are made.

45 1 is the arch of a Garnett machine. 2 are the detachable segmental plates, which are secured to the arch by the bolts 3 and nuts 4, as clearly shown in Fig. 2. These bolts pass through holes 5 formed in the 50 plates 2 and they are of a sufficient length to retain a poppet 6 to the plates by means of the nuts 7. The poppet supports the bearing 8 for the shaft 9, on which is mounted one of the small rolls 10 of a Gar-

nett machine. These rolls partially surround the main cylinder 11, shown by dotted lines, and are provided with garnett teeth in the ordinary manner. The plates 2, in the present instance, are struck up from sheet metal. Each plate has two projections 12 at the upper end and two projections 13 at 55 the lower end. The projections 12 act as abutments for the set screws 14, which extend through the flanges 15, and, on turning these set screws, each poppet can be laterally 60 adjusted. The lower projections 13 are cut to receive the fixed nuts 16 through which the longitudinal adjusting screws 17 extend. These adjusting screws have flanges 18 and 19 spaced apart and a forked projection 70 20 of the poppet extends between the two flanges 18 and 19. The adjusting screw has a head 21, on turning which the poppet can be longitudinally adjusted.

While the plates may be made in any 75 manner desired, we prefer to make them of sheet metal, or bend them from a flat plate punched, as shown in Fig. 6, which, after being punched, is bent into shape, as shown in Fig. 3. We may place filling blocks 22 80 in the recesses of the projections 12, if found desirable. If the plates are made of comparatively heavy metal, the filling blocks are unnecessary.

The nuts 16 are made as shown in Fig. 85 5 and are cut away at 23 forming lugs 24, which extend on each side of the projections 13, the projections being cut to receive the lugs. This makes a very rigid construction 90 and one which will allow for the ready adjustment of the individual poppets, as well as the adjustment of each pair of poppets.

When it is desired to adjust any of the plates, this can be accomplished by detaching the nuts 7 to remove the poppet and 95 loosening the nuts 4 to allow for the adjusting of the plates. This construction simplifies the manufacture of a Garnett machine, as, instead of the complicated casting heretofore required to form an arch, 100 a plain one can be used to which the plates are secured.

Furthermore, the poppets can be adjusted on the plates without loosening the plates.

We claim:

1. The combination in a Garnett machine, 105 of an arch; a series of plates mounted on the face of the arch, said plates having pro-

jections; poppets mounted on the plates; bolts extending through the plates and through the poppets; and two nuts on each bolt, one holding the plate to the arch and the other holding the poppet to the plate and to the arch.

2. The combination in a Garnett machine, of an arch; a series of plates secured to the arch, each plate having two sets of projections; a hole between each set of projections;

a fixed nut held by each of the lower projections; adjusting screws passing through the nuts; poppets having projections engaging the adjusting screws and having set screws bearing against the upper projections, the set screws adjusting the poppets laterally, the other screws adjusting the poppets longitudinally. 15

WILLIAM F. BOKUM.

HERBERT V. COULSTON.
